CALIFORNIA

AGITATOR

Application filed December 3, 1928. Serial No. 323,288.

This invention relates to a combination agitator and mixer, and especially to an agitator which maintains heavy substances, such as concrete, mortar and the like, 5 thoroughly mixed while in transit or while awaiting use.

The object of the present invention is to generally improve and simplify the construction and operation of agitators and mixers, 10 to provide an agitator and mixer which is particularly adapted for handling heavy substances such as cementitious mixtures, for instance concrete containing heavy aggregates such as crushed rock and sand, etc. and 15 further to provide an agitator and mixer in which agitation and mixing is obtained by rotary impellers which not only impart a rotary movement to the material being mixed, but also a vertical movement.

20 The agitator and mixer are shown by way of illustration in the accompanying drawings, in which:

Fig. 1 is a central vertical section of the agitator and mixer,

25 Fig. 2 is a cross section taken on line II—II

Fig. 1,

Fig. 3 is a section taken on line III—III

Fig. 1,

Fig. 4 is a section taken on line IV—IV

30 Fig. 1,

Fig. 5 is a section taken on line V—V

Fig. 6.

Fig. 6 is a section taken on line VI—VI

35 Fig. 5, said section showing the chain drive in side elevation,

Fig. 7 is a side elevation of the central steering blade.

Referring to the drawings in detail, particularly Fig. 1, A indicates a tank or like 40 receptacle adapted to contain materials to be agitated and mixed. Mounted on top of the tank is a cover plate 2, and secured to the under side of the cover plate is an internal gear 3. Extending through the cover plate 45 and journaled therein is a drive shaft 4, to which power may be transmitted in any suitable manner, for instance, through a sprocket gear 5. Mounted on the drive shaft is a head member generally indicated at B, this head 50 member consisting of a bottom plate 6 and

a top or cover plate 7. This head member is adapted to freely rotate with relation to the drive shaft, and the manner of rotating the same will hereinafter be described.

Secured on the drive shaft intermediate 55 the top plate 7 and the cover 2 is a driving pinion 8. Secured in the top plate 7 are a pair of stud pin bearings 9, and journaled thereon are intermediate gears 10, these gears meshing with the driving pinion 8 and 60 with the internal gear 3. Hence, if rotary motion is transmitted to the drive shaft and pinion 8 in the direction of arrow *a*, see Fig. 3, rotary movement will be transmitted to the head member B in the same direction 65 as arrow *a*, as the intermediate ears 10 mesh with the driving pinion 8 and with the stationary internal gear 3. The head member B is supported with relation to the drive shaft by means of a collar 11, secured 70 on the lower end of the shaft, and by intermediate anti-friction thrust bearings such as indicated at 12. These thrust bearings take up all downward thrust of the head while rollers 13 journaled exterior of the stationary 75 ring gear absorb all upward thrust.

Journaled at the opposite ends of the head member B in bearings indicated at 14, are downwardly extending vertically disposed shafts 15. Secured on the lower ends of each 80 shaft are rotors or impellers 16, and secured on the upper ends of the shafts intermediate the plates 6 and 7 are sprocket gears 17. A driving sprocket gear 18 is secured on the drive shaft 4 and an endless sprocket chain 19 85 is passed around this gear and the sprocket 17, the chain also passing over idlers 20, one of which is adjustable, as indicated at 21 to take up any slack that may occur. A chain 19 transmits a rotary movement to the shafts 90 15 and the impellers 16, and as the gear ratio shown at 8, 9 and 3 is comparatively low with relation to the gear or sprocket chain ratio between the sprocket gears 17 and 18, each impeller 16 will make several revolutions during each revolution of the head member B.

The impellers serve the function of maintaining the contents of the tank A in a 95 thoroughly mixed and agitated condition re- 100

5 gardless of what the material may be, but for the purpose of describing one use of the device it might be stated that the tank may be mounted on a truck or like motor vehicle and that it serves the purpose of conveying concrete from one point to another. The impellers are continuously rotated while the load of concrete is in transit and it thus maintains the concrete in a thoroughly mixed and 10 homogenous condition so that it is ready for use the moment it arrives at its destination. Concrete of course usually contains heavy aggregates, such as crushed rock, gravel, sand, etc. Such aggregate tends to settle to 15 the bottom of the tank during transit but the employment of an agitating and mixing device such as here shown prevents such settling as the rotors or impellers are provided with a plurality of inclined blades, such as shown 20 at 16^b. These blades impart a rotary mixing action to the concrete and due to the inclined surface presented by the blades they also tend to impart an upward vertical movement, thus continuously elevating the heavier aggregates 25 which have a tendency to settle.

By referring to Figs. 1 and 2 it will be noted that a plate C is secured to the base plate 6 of the head member. The plate C extends downwardly between the impellers 16 and it serves the function of more thoroughly distributing the material which is being stirred and agitated by means of the impellers. The blade or plate C is substantially S-shaped in cross section, as shown in Fig. 35 2. The concrete or material maintained in motion by the impeller indicated at 16 strikes one side of the plate in the direction of arrow b and as such is deflected and discharged by the plate in the direction of arrow c. The material maintained in motion by the impeller indicated at 16^a strikes the plate in the direction of arrow d and is discharged outwardly thereby in the direction of arrow e. The plate thus functions to uniformly 40 distribute material throughout the body of the tank, and it might be stated that the distribution is radial with relation to the center point of the plate, as the plate is attached to the head member B and the head member 45 B continuously rotates.

50 While the agitator and mixing device has been described in conjunction with concrete, it is obvious that it may be used in conjunction with bituminous mixes and for numerous other purposes, for instance in the paint industry, etc.

In Figs. 1 and 3 the head is shown as positively rotated through a planetary gear transmission, to wit the gears 3, 8 and 10. In Figs. 60 5 and 6 a chain transmission alone is employed and it serves the function not only of rotating the impellers indicated at 16^b and 16^a but also that of rotating the head member B. If reference is made to Fig. 5 it will 65 be noted that the impeller 16^b rotates in the

direction of the arrow. The inclined surface of the impeller 16^b is pushed against the concrete in the direction of arrow f, and as the head is freely rotatable on the drive shaft, it tends to rotate in the direction of arrow h. In other words, the inclined blades of the impeller 16^b react to rotate the head. The impeller 16^a rotates in the direction of the arrow indicated, and it reacts in a similar manner with the concrete and thus tends to 70 impart rotary motion to the head B in the direction of the arrow h. The head is thus automatically rotated without any positive gear transmission such as employed in Fig. 1.

In summing up the operation of the agitator and mixer, it will be noted that mixing action and agitation is not only obtained by means of the inclined blades of the rotors or impellers 16 and 16^a, but it is also obtained by rotation of the head and the plate C, the plate C further serving the function of continuously directing the materials being mixed 75 radially in all directions as the blade and head are rotated.

80 The inclined blades of the impeller do not only impart a rotary mixing action to the material, but they also produce a vertical movement to the material, thereby preventing the heavier ingredients from settling to the bottom. Where upward movement is not so essential a horizontal deflector plate is employed, as indicated at 35, see Figs. 1 and 2, this plate retarding upward movement 85 of the material as it strikes the plate C. A uniform homogeneous mixture may thus be maintained while material is in transit or while awaiting use, and homogeneous mixtures may also be obtained by merely placing 90 them in the tank and subjecting them to the mixing and agitating action described.

95 While certain features of the present invention are more or less specifically described, we wish it understood that various changes may be resorted to within the scope 100 of the appended claims, similarly, that the materials and finishes of the several parts employed may be such as the manufacturer 105 may decide, or varying conditions or uses may demand.

110 Having thus described our invention, what we claim and desire to secure by Letters Patent is:

115 1. In a device of the character described a drive shaft, a head member journaled on 120 said shaft, an impeller depending therefrom, a pair of impeller shafts journaled in the head, an impeller secured on each shaft, a sprocket gear secured on the drive shaft, a 125 pair of sprocket gears secured one on each impeller shaft, a pair of idler wheels journaled on the head, one on each side of the drive shaft and a chain passing over the sprocket gears on the impeller shafts and the idler wheels and passing around one side 130

of the sprocket gear on the drive shaft whereby said sprocket gear on the drive shaft and the chain will impart a rotary motion to the impeller shafts in one direction and a rotary motion to the head in an opposite direction.

2. In a device of the character described a drive shaft, a head member journaled on said shaft, an impeller depending therefrom, a pair of impeller shafts journaled in the head, an impeller secured on each shaft, a sprocket gear secured on the drive shaft, a sprocket secured on each impeller shaft, a single chain embracing the sprockets on impeller shafts and engaging the sprocket on the drive shaft, whereby a drive transmitted to the drive shaft will cause rotation of the head in one direction and rotation of the impeller shafts in the opposite direction.

CHARLES F. RODIN.
